UNITED STATES PATENT OFFICE.

WILLIAM MUELLER, OF FREDERICKSBURG, TEXAS.

JAR CLOSURE.

Application filed August 22, 1921. Serial No. 494,158.

To all whom it may concern:

Be it known that I, WILLIAM MUELLER, a citizen of the United States, residing at Fredericksburg, in the county of Gillespie 5 and State of Texas, have invented a new and useful Jar Closure, of which the following is a specification.

This invention relates to jar closures.

The object is to provide a jar and closure 10 therefor composed entirely of glass to accord with sanitary requirements and dispense with the use of the rubber ring or gasket, the neck or mouth of the jar and the closure having interfitting and coacting 15 parts so formed as to permit of an air-tight joint therebetween after the fruit, vegetables or other contents of the jar have become cooled, after sterilization.

Another object is to provide a device 20 of this character which, by reason of the simplicity of its construction, may be produced at a low cost and will require no skill in the application of the closure to the jar to produce the desired air-tight joint.

25 A full and complete understanding of the invention may be obtained from a consideration of the following detailed description taken in connection with the accompanying drawing forming a part of this specification, it being understood that while the drawing 30 shows a practical form of the invention, the latter is not confined to strict conformity therewith, but may be changed or modified, so long as such changes and modifications 35 mark no material departure from the salient features of the invention, as specifically pointed out in the appended claims.

In the drawing,—

40 Figure 1 is an inverted plan view of the closure for the jar.

Figure 2 is a plan view of the jar.

Figure 3 is a vertical section through the upper portion of the jar and showing the closure applied thereto and held by the 45 temporary clamping ring, prior to the application of the sealing wax.

Figure 4 is a similar view taken at right angles to Figure 3.

Figure 5 is an enlarged sectional view 50 through one side of the mouth of the jar and the closure and showing the manner of applying the sealing wax.

Referring particularly to Figures 3, 4 and 5, of the drawing, there is illustrated the 55 upper portion of an ordinary glass fruit or vegetable jar 1, though, of course, it will

be understood that the invention may be applied to containers of other classes as well.

The jar is provided with a reduced neck 60 provided with an unobstructed mouth having the outwardly-extending, annular flange 2 surrounding the same to provide ample space for an annular channel 3 formed in the upper face of the said flange and neck. 65

The said channel 3 extends entirely around the jar and is easily produced in the usual manner in the formation of the jar. The outer wall 4 of the channel 3 is upwardly and outwardly inclined at an 70 obtuse angle to the bottom of said channel, and the inner wall 5 of said channel is likewise inclined at an obtuse angle with relation to the bottom of the same, as clearly shown in Figure 5 of the drawing, but is shorter 75 than the outer wall.

The bottom wall of the annular channel 3, as well as the inner wall 5 thereof are preferably ground in a well-known manner, for the purpose of producing an air-tight joint 80 in coaction with certain parts carried by the closure for the jar.

The upper end of the inner annular wall 5 of the channel 3 communicates with an inwardly-extending, supplemental channel 6, 85 formed by the provision of an inwardly-directed step terminating short of the adjacent inner wall of the neck of the jar, and resulting in the provision of an up-standing annular rib or flange 7 whose inner wall is co-extensive with said inner wall of the neck of the jar and extends entirely around the same. 90

The upper edge of the rib or flange 7 is 95 on a horizontal plane with the upper edge of the rib 8, formed between the outer inclined wall 4 of the main channel and the outer face of the flange 2, and the said rib 8 preferably has its upper edge rounded as shown, so as to prevent chipping of the glass 100 when the jar is being opened in a manner to be described.

The closure or cap 9 for the jar comprises a solid glass disc of a diameter somewhat less than the external diameter of the mouth of the jar, and said cap or closure is provided at a point adjacent to its periphery with an annular, depending flange 10 on its under side and formed integrally therewith, the said flange having its outer and inner 110 sides 11 and 12 respectively inclined in substantial parallelism with the walls 4 and 5

of the aforesaid channel 3 formed in the mouth of the jar.

The inner wall 12 of the flange 10 of the cap or closure is preferably ground around its lower portion as well as the bottom wall 13 of the same, in a manner similar to the bottom of the channel 3 and the inner wall 5 thereof, for the purpose of coacting therewith and forming an air-tight joint at this point, when the closure is applied to the mouth of the jar, it being necessary, of course, that the proportions of the closure shall be such that the said walls will interfit in the desired manner.

15 Between the outer wall 11 of the closure flange 10 and the outer peripheral edge of said closure or cap an overhanging shoulder 14 is provided, a space being formed between the said peripheral edge of the closure 20 and the adjacent outer, inclined wall 4 of the channel 3 formed in the upper face of the jar for a purpose to be explained.

The closure 9 is provided on its upper face with an integral, transverse, upstanding rib 15 extending from edge to edge thereof and diametrically through the center of the same, said rib being provided for the purpose of supporting and upholding the central portion of a spring clip 16 extending diametrically across the closure, after the same has been applied to the jar, and at right angles to said rib 15. The outer ends of the spring clip, which is preferably formed of a flat strip of spring steel or other suitable metal, are bent downwardly to form arms 17 which lie adjacent to the outer opposite faces of the annular flange 2, and terminate at their lower ends in inwardly directed hooks 18, adapted to engage beneath the underside of said flange 2, after the body portion of the spring clip 16 has been somewhat flexed in a well known manner, to rigidly hold the closure in its seat upon the upper end of the jar.

40 At one end, the rib 15 is provided with an aperture 19 and an integral lug 20, formed beneath the annular flange 2 at the mouth of the jar is also provided with an aperture 21, these perforations being adapted to receive a wire or similar device for tying the closure to the jar so that they may not become separated, it being necessary that the same closure be used at all times on its particular jar.

55 The spring 16 exerts a pressure of about one pound per square inch on the cover or closure to prevent the juices of the contents of the jar from escaping from the jar while in the operation of sterilizing.

60 The ground joints heretofore referred to on the jar and the closure form an air-tight joint, as soon as pressure is greater on the outside than on the inside of the jar due to superior atmospheric pressure, upon the cooling of the contents of the jar, and while

the latter is taking place the aforesaid supplemental channel 6 retains some of the condensed steam while a vacuum is forming at the same time in the jar. The atmospheric pressure upon the outside of the jar will cause air to enter through any defective places in the ground joint and passing through the condensed steam in the supplemental channel 6, the entering air will form bubbles, thus indicating the defect in time to be corrected.

The space heretofore referred to between the closure flange 10 and the outer wall of the channel 3, is for the purpose of receiving a quantity of sealing wax A, which may be introduced in a melted condition through the space between the outer periphery of the closure disc and the outer rib 8 of the jar; and this wax is applied directly upon being taken from the sterilizer and is allowed to harden and remain in place to further assist in maintaining an air-tight joint.

45 The inclined walls 11 and 12 of the flange 10 carried by the closure facilitate the removal of the latter from the jar when it is desired to use the contents of the latter, it being only necessary to introduce a knife blade B or other instrument beneath the peripheral shoulder 14 of the closure, and fulcrum the same upon the marginal rib 8 of the jar, at any point around the same, and by a prying action, the closure may be readily removed, said instrument being readily introduced in this manner by reason 50 of the fact that the lower face of the closure is slightly above the upper edge of the rib 8 and is spaced inwardly therefrom. It is only necessary to admit a small amount of air in this manner when the closure will readily become detached, after the vacuum 55 on the inside has been broken.

60 From the foregoing it will be seen that a simple and cheaply manufactured jar closure has been provided which may be easily applied to the jar to form an air-tight joint, and by reason of the methods followed in modern canning processes, the said joint will be maintained until the above-described method of opening the jar has 65 been followed. The joint is produced without the use of the expensive rubber rings or gaskets, the spring clip being used only during the process of sterilizing to prevent the egress of the juices, and may or may not 70 be left on the jar as desired.

65 What is claimed is:

1. The combination with a jar having an annular channel formed in the upper surface of its neck and surrounding the open mouth thereof, said channel having inclined outer and inner walls, and a supplemental annular channel formed above the other channel and between it and the mouth of the jar, of a closure for the jar comprising 75

a solid glass disk having on its under side an annular tapered flange of a depth greater than the combined depth of said channels and of a diameter to seat itself in the first-
5 named channel of the jar, with the inner wall of the flange engaging the inner wall of the first-mentioned channel, and the bottom thereof resting on the bottom of said channel, and with the under surface of the disk
10 spaced from the upper inner edge of the neck whereby moisture from the inside of the jar may pass into and become condensed in the supplemental channel to form a liquid seal.
2. The combination with a jar having an
15 annular channel formed in the upper surface of its neck and surrounding the open mouth thereof, said channel having inclined outer and inner walls, and a supplemental annular channel formed above the other channel and
20 between it and the mouth of the jar, the bottom and inner wall of the first-mentioned channel being ground, of a closure for the jar comprising a solid glass disk having on its under side an annular tapered flange,
25 the bottom and inner wall of which are ground, said flange being of a depth greater than the combined depth of said channels and of a diameter to seat itself in the first-mentioned channel of the jar, with the inner
30 wall of the flange engaging the inner wall of the first-mentioned channel, and the bottom thereof seated on the bottom of said channel and with the under surface of the disk
35 spaced from the upper inner edge of the neck whereby moisture from the inside of

the jar may pass into and become condensed in the supplemental channel to form a liquid seal.

3. The combination with a jar having an
40 annular channel formed in the upper surface of its neck in surrounding relation to the open mouth thereof, said channel having inclined inner and outer walls and a supplemental annular channel formed above the other channel and between it and the mouth
45 of the jar, of a closure for the jar comprising a solid glass disc having on its under-side an annular depending tapered flange of a diameter to seat itself in the channel of the jar, with the inner wall of the flange
50 engaging the inner wall of said channel and the bottom thereof resting on the bottom of said channel, the width of said channel being greater than the width of said flange, so as to provide a space between the outer wall of the flange and the outer wall
55 of the channel in which to place sealing wax, the height of the flange being greater than the depth of the channel, so that a space is left between the upper wall of the neck
60 and the bottom wall of the closure for the insertion of an instrument to remove the closure, and whereby a space is also left between the bottom wall of the closure and the inner edge of the neck to permit a seal of
65 supplemental channel.

In testimony that I claim the foregoing as my own, I have hereto affixed my signature.

WILLIAM MUELLER.
